UNITED STATES PATENT OFFICE.

GEORGE ROBERT PRATT, OF WINNIPEG, MANITOBA, CANADA.

FIRE POT.

1,412,133.

Specification of Letters Patent. Patented Apr. 11, 1922.

Application filed September 26, 1918. Serial No. 255,830.

To all whom it may concern:

Be it known that I, GEORGE ROBERT PRATT, of the city of Winnipeg, in the Province of Manitoba, Canada, have invented certain new and useful Improvements in Fire Pots, of which the following is the specification.

The invention relates to improvements in fire pots of stoves, furnaces and the like and the principal object of the invention is to provide a means insertable or contained within the fire pot which will render it possible, by proper firing, to get an effective combustion of the fuel, thereby rendering the furnace more efficient and saving materially in the consumption of fuel and rendering it possible to burn low grade and slack coals in house furnaces without the danger of exploding gases.

With the above object in view the invention consists essentially in a divisional member inserted in the fire pot and crossing the same to divide the fire, the parts being arranged and constructed as hereinafter more particularly described and later pointed out in the appended claims, reference being had to the accompanying drawing in which:—

Fig. 1 represents a vertical sectional view through the fire pot and combustion chamber for burning the gases of a furnace showing my invention installed.

Fig. 2 represents a sectional view through the fire pot and combustion chamber, the section being taken in the plane denoted by the line X—X' Fig. 1.

Figures 3, 4, 5 and 6 represent diagrammatically the fire in several stages.

In the drawing like characters of reference indicate corresponding parts in the several figures.

1 represents a furnace of which 2 is the fire pot, 3 the fire door, 4 the customary grates and 5 the flue.

According to present practice the fuel such as coal is placed on the grates to a more or less even level within the pot, depending on the depth of fire required. According to my invention I place a structure composed of refractory material such as fire brick or cast iron in the pot of the furnace or stove as the case may be in such a manner that it divides the fuel space into two or more compartments. The structure may or may not project above the top of the fuel

bed but the bottom of it is kept clear of the grates a distance sufficient to allow of a continuous bed of fire under the structure.

The said structure is indicated in the drawing at 6 and comprises a divisional plate of fire brick or cast iron which passes across the fire pot and has the ends thereof tapered to fit the customary tapering sides of the fire pot. The length of the plate is such that it sits in the fire pot with the lower edge 7 thereof elevated a short distance above the grates to allow of a fire bed under the structure.

The invention is particularly useful for burning soft coal as, by utilizing it I am enabled to release the gases and mix them with a sufficient quantity of air to support combustion and to create a high temperature which will ignite and burn the gases.

In building a fire in my fire pot the coal is initially built on the grates up to or slightly above the level of the lower edge of the divisional member and is initially fired. Then coal is thrown into say the left hand side of the pot up to say the level of the top of the divisional board in which condition it is shown in Fig. 1. With this condition it will be seen that at the right hand side of the divisional member I have a comparatively low fire bed which is burning freely owing to the fact that ample air draft passes therethrough, such coming up through the grates and that at the left hand side where there is not such a draft, owing to the increased depth of coal, the fire is working up gradually from the bottom.

As the fire continues burning the coal on the left hand side becomes heated and liberates the gas, the greater part of the heat coming from the more or less intense fire at the right hand side.

It is a well known fact that the gases given off from the fuel especially soft coal of high volatile content must be properly mixed with the oxygen of the air which is admitted over the fire, in order to consume the same gases. There are various means in present day practice of mechanically mixing these gases and air, such as with fans, air jets and steam jets in order to obtain the proper combustion.

It is also well known that a hot body will create a current of moving gases upward

and that with the flow of hot gases up from this source of heat is created a flow of cooler gases towards the source of heat.

A feature in the operation of my invention 5 is as follows:—The divisional member having become heated by the hot fire on the one side and under, automatically acts in the same manner as would a fan or steam jet and creates a current of heated gas directly 10 over and off the top of same, this in turn causes the unconsumed gases from the coal and the cooler air which has been admitted into the furnace to flow down towards the hot divisional member where upon mixing 15 with the hot gases arising from same becomes ignited.

Another feature of my invention is the process of distilling the volatile gases out 20 of the coal before the fuel is burned in the fuel bed. Owing to the nature of the structure of the partition, heat is transferred slowly through the same. When the fuel is first placed in the fire pot at one side of the partition, the slow rise in temperature 25 of the fuel, distils the moisture out of the fuel before the combustible gases are driven out and as they are driven out without coming in contact with the burning fuel they are dispersed without lowering the temperature of the fire bed. The second period of 30 distillation drives out the combustible gases, and after these are all distilled the fuel burns in the bed of the fire in a similar manner to coke or hard coal.

35 Due to the location of the division member in the bed of the coal and the comparatively slow transfer of the heat from one side to the other, one side may be at a necessary high rate of combustion. When this side is 40 burned down the other side has automatically attained a similar high rate of combustion thus allowing a much longer period between firing without attention.

In Fig. 3 I have shown diagrammatically 45 the appearance of the fire a short time after firing where it will be observed that approximately half the coal in the left hand side of the pot has been coked. In Fig. 4

I have shown the coal in the left hand side of the pot entirely coked.

When the fire is in the state as shown in Fig. 4 the fireman then fills the right hand side of the pot with new coal as shown in Fig. 5 and the gases from this coal are driven off by the intense heat developed in 55 the left hand side of the pit and are consumed.

Fig. 6 shows the state of the fire as it would appear with both sides coked and as it would be left, say for the night.

This alternate firing to opposite sides of the divisional member is continued as long as the furnace is in use.

I have not shown any particular means for bringing in new air on the top of the fire 65 and it is to be understood that sufficient air for proper combustion leaks in around the fire door and through the grates.

Whilst I have shown a single divisional member, it will be readily understood that 70 the fire pot could be divided up into more than two compartments and that the coal could be fired into the various divisions one after the other as explained in connection with the two divisions.

Further, whilst I have shown the divisional member as a single piece I wish it to be understood that it could be made in sections fitted to accommodate contraction and expansion.

What I claim as my invention is:—

A fire pot having a centrally positioned vertically disposed divisional member of refractory material crossing the same and dividing the pot into two distinct firing compartments opening at the top to a common combustion chamber and with the divisional member elevated above the grate to permit of a single continuous bed of fire under both compartments.

Signed at Winnipeg, this 7 day of September 1918.

GEORGE ROBERT PRATT.

In the presence of—

G. S. ROXBURGH,
K. B. WAKEFIELD.
